(57) **CLAIM**

I claim the ornamental design of a reading lamp connector, as shown and described.

DESCRIPTION

FIG. 1 is a top perspective view of a reading lamp connector showing my new design with a first configuration of a connector socket;

FIG. 2 is a top plan view of the reading lamp connector shown in FIG. 1;

FIG. 3 is a top perspective view of a reading lamp connector showing my new design with a second configuration of a connector socket;

FIG. 4 is a top plan view of the reading lamp connector shown in FIG. 3;

FIG. 5 is a bottom perspective view of the reading lamp connector shown in each of FIG. 1 and FIG. 3;

FIG. 6 is a bottom plan view of the reading lamp connector shown in each of FIG. 1 and FIG. 3;

FIG. 7 is a first side view of the reading lamp connector shown in each of FIG. 1 and FIG. 3;

FIG. 8 is a second side view of the reading lamp connector shown in each of FIG. 1 and FIG. 3, rotated to the left relative to the first side view of FIG. 7; and,

FIG. 9 is a third side view of the reading lamp connector shown in each of FIG. 1 and FIG. 3, rotated to the left relative to the second side view of FIG. 8.

The broken lines in the drawings illustrate portions of the reading lamp connector that form no part of the claimed design.
